CLOTHES DRIER WITH HORIZONTAL CYLINDER

Paul L. Fowler, Portland, Oreg.

Application February 20, 1952, Serial No. 272,630

4 Claims. (Cl. 34—82)

1

This invention relates generally to clothes dryers and particularly to a clothes drier of the tumbling type in which the drier is mounted on a horizontal axis.

An object of this invention is to provide a drier of sufficient capacity to handle a complete washer load at one time.

The second object is to subject the clothes to a gentle tumbling action which will raise the clothes and gently lower them across a steady flow of fresh drying air.

The third object is to construct a drying cylinder which will minimize the wear on the fabrics by presenting a smooth porcelain enamel surface instead of a screen or a relatively rough galvanized surface.

The fourth object is to provide a maximum size of door opening allowing easy accessibility to the cylinder and to employ a convex glass door to assist in the rotation of the clothes from the front to the back of the cylinder at the same time they are moving in a counter-clockwise direction.

The fifth object is to provide an air intake and blower system in which air is taken in at the bottom front of the machine and the air is then drawn across the base and into the air duct containing the heating elements. The air is set in motion by a fan of sufficient capacity to allow for outdoor venting through the exhaust system and in which the intake and exhaust ports are disposed as remotely as possible.

The sixth object is to use a sag-proof coil type of element which operates at a black heat thus insuring long life for the heating elements; that is, no glow is visible.

The seventh object is to provide an oversized lint trap. Top and rear vents are provided which facilitate installation, and the electrical outlet at the rear of the base permits connecting the drier without removing the back panel.

The eighth object is to provide a reversible door for right and left-hand openings.

The ninth object is to provide certain safety features including an automatic motor overload switch and an element thermostat switch which cuts elements off at 180° in the event of motor failure and prevents possible damage to the clothing, and also a door actuated switch which cuts out motor and shuts off heat when door is opened.

The tenth object is to construct the cabinet as to give maximum accessibility which requires only the removal of the front panel to permit the removal of the cylinder and exposing the entire interior for servicing.

The eleventh object is to provide an improved form of triple cylinder seal.

2

The twelfth object is to provide a special trunnion gear cylinder mounting whereby there is eliminated a main bearing against which a load of from 68 to 70 pounds must be supported.

The thirteenth object is to provide a single dial control providing for time and temperature desired at only one dial setting. Provision is also made for automatic shut-off for any desired dryness or type of fabric.

These and other objects are accomplished in the manner set forth in the following specifications as illustrated in the accompanying drawings, in which

Fig. 1 is a perspective view of the exterior of the drier.

Fig. 2 is a perspective view of the frame showing the hot air inlet, the exhaust fan opening and the rollers upon which the cylinder rests.

Fig. 3 is a section along the line 3—3 in Fig. 1.

Fig. 4 is a perspective view of a hinge.

Fig. 5 is a perspective view of the drive from the motor to the exhaust fan and driving rolls.

Fig. 6 is a vertical section taken along the line 6—6 in Fig. 1.

Fig. 7 is a fragmentary perspective of the heater.

Fig. 8 is a perspective view of the upper portion of the exhaust stack showing the lint trap, thermostat and vent hole.

Fig. 9 is a rear elevation of the drying cylinder taken along the line 9—9 in Fig. 6.

Fig. 10 is a section through the seal taken along the line 10—10 in Fig. 9.

Fig. 11 is a fragmentary rear elevation of the loading door opening showing hinge mounting lugs on each side so that the door can be mounted to swing right or left to suit the user.

Fig. 12 is a vertical section taken along the line 12—12 in Fig. 6.

Like numbers of reference refer to the same or similar parts throughout the several views.

Referring in detail to the drawings, there is shown a base 20 having the downturned flange 21 and the upturned side frames 22 which are joined by the back plate 23 and the low front frame 24 on which are mounted the cylinder supporting idler rolls 25. The rolls 25 are mounted on the shaft 26 which journals in the plates 23 and 24, and the driver rolls 27 and 28 which are mounted on the drive shaft 29 on which is secured a V-grooved pulley 30 which is driven by a belt 31 from the double-grooved pulleys 32 on the motor 33 mounted on the base 34. The wall 35 has a closed front 36 having an opening 37 provided with an outturned flange 38 around which is secured a resilient sealing plate 39. The opening

37 constitutes the loading and unloading opening for the cylinder 40. The cylindrical outer wall 35 rests upon the rolls 25, 27 and 28 and can rotate thereon when driven by the motor 33.

The rear end of the cylinder 40 is provided with an inturned flange 41 having an outturned lip 42 over which is placed a head 43 of wire cloth in the center of which is placed the rear deflector 44 which is convex on its forward side and has a disk 45 on its rearward side which is held in place by a bar 46 and the metal screws 47 which pass through the head 43 into the disk 45.

Radially disposed across the head 43 are the resilient sealing strips 48, one side of which is held by the strips 49 and U bolts 50 to the head 43, while the portion 51 of the seal 48 bears against the back plate 23. Encircling the lip 42 at its surrounding bead from the head 43 is a sealing collar 52 which bears against the back plate 23 and is held in place by means of a wire 53.

Within the cylindrical wall 35 are the tumbling vanes 54 preferably spaced midway between each pair of sealing strips 48. Surrounding the cylindrical wall 35 is a blanket of insulating material 55 held in place by the bands 56.

Secured to the flanges 21 by means of the screws 57 are the cabinet sides 58 which are joined by a back 59 secured to the flanges 21 by means of the screws 60.

The front plate 24 is secured to the flange 21 by means of the screws 61. A front 62 connects the sides 58 and terminates at its lower end 63 on a level with the outturned flange 64 of the front plate 24. The front 62 has a rectangular door opening 65 formed therein having a recessed portion 66 for the rectangular door 67. The door opening 65 is provided, along both opposite vertical edges, with angle clips 68 containing a pin 69 upon which a semi-circular hinge 70 and its radial arm 71 can swing while the outturned arm 72 is attached to one side of the door 67 enabling the door to swing right or left handed.

The door 67 is provided with a circular flange 73 in which is inserted a transparent front deflector 74 which is held in place by the outer door facing 75. A seal 76 is placed between the door 67 and the contacting face of the recess 66. A suitable handle 77 is provided for the swinging side of the door 67.

The back frame 23 is provided with an opening 78 which registers with the motor 33. Above the shaft 29 is formed an opening 79 for the exhaust fan 80 contained within the casing 81 and mounted on the shaft 82 on which is secured a belt pulley 83 which is driven by the belt 84 from the motor pulley 32.

In the back plate 23 is a hot air inlet opening 85 which is at the upper end of a stack 86 whose rounded top 87 terminates at the upper edge of the opening 85, while the curved baffle 88 terminates approximately in the middle of the opening 85 and serves to break up the concentration of air in the upper portion of the cylinder due to centrifugal action.

In the stack 86 is formed an opening 89 having a cover plate 90 secured thereto by means of the screws 91. From the cover plate 90 project the side plates 92 between which are the tie bars 93 which, together with the clamps 94, are bent to form the openings 95 for the insulators 96 which are occupied by the resistance element 97 connected to a suitable source of power under the control of a thermostat 98 for controlling the various amounts of heat delivered to the drier 75

but, since such thermostats are well understood, they will not be discussed specifically here since they form no part of the present invention.

On the front 62 is provided a control switch 99 whereby the speed of the motor 33 can be controlled to regulate, to any desired degree, the tumbling action within the cylinder 40.

Secured to the back of the rear frame 23 is a stack 100 having a horizontal floor 101 therein through which extends the upturned duct 102 through which heated air coming from the compartment 103 passes upwardly into a wire cloth lint trap 104 having a cover 105. The lint trap 104 has an outturned flange 106 which rests upon the top 107 of the stack 100, shown in broken section in Fig. 8. An air outlet duct 108 opens outwardly through the top 107 and provides a means of escape of the air passing through the lint trap 104 and outwardly into the atmosphere.

A top 109 covers the entire cabinet and is held in place by means of the screws 110.

The operation of the device is as follows: Assuming that a quantity of moist clothes is placed within the drying cylinder 40 and that the thermostatic switch 98 is set at the desired temperature and the switch 99 turned to cause the motor 33 to rotate at a desired speed, it will be seen that air is drawn by the exhaust fan 80 from the cylinder 40 and replaced by air heated by the elements 96 and discharged through the opening 85 into the upper portion of the cylinder 40 at different levels owing to the baffle 88. It will be observed that as the cylinder 40 is revolved and the clothes carried upwardly to a tumbling point instead of remaining in a single fixed vertical plane, those nearest the corners of the cylinder will fall upon the rear deflector 44 or the front deflector 74 and encouraged to move toward the middle of the drying cylinder, and all the time they are given a gentle agitating and aerating movement which shortens the drying time and is not injurious to the fabrics. The lint itself is collected in the lint trap and can be removed by simply lifting out the trap and disposing of the lint in any desired manner.

I am aware that many forms of clothes dryers have been constructed in the past. It is, therefore, not my intention to cover such devices broadly but I do intend to cover all such forms and modifications thereof as fall fairly within the appended claims.

I claim:

1. A clothes drier of the class described having in combination a supporting structure including an upright back frame and a cradle of supporting driving rolls supported by said structure, an imperforate cylinder mounted on said rolls, the forward end of said cylinder having a loading opening along its axis and the other end of said cylinder having a perforated head, both ends of said cylinder having inwardly curved deflectors, the cylindrical portion of said cylinder having inwardly extending tumbling vanes, radial sealing strips on said perforated head adapted to engage said back frame, said back frame having a hot air inlet and a moist air outlet opening formed therein within the area swept by said sealing strips, means for delivering heated air to said hot air inlet and means for extracting moist air from the moist air outlet, together with means for extracting lint from said moisture laden air.

2. A clothes drier comprising a cabinet having a pair of shafts in the lower portion thereof, each

of which has a pair of rollers mounted thereon, an imperforate cylinder resting on said rollers and revolvable thereby, one end of said cylinder consisting of a head of wire cloth, said head being divided into a plurality of separate sections by means of radial sealing strips, a back plate adjacent to said wire cloth head and engaging said sealing strips, said back plate having hot air inlet and moist air outlet openings formed therein within the circumference of said cylinder, means for heating air and delivering it through said inlet opening into the upper portion of said cylinder and a lint removing moist air outlet substantially opposite said hot air inlet.

3. A clothes drier of the horizontal cylinder type having in combination a supporting frame, an imperforate cylinder supported by said frame, rollers engaging the exterior of said frame, a wire cloth head for one end of said cylinder, a

seal around said head engaging said frame, radial seals on said head dividing it into a plurality of sectors, said frame having an inlet opening for heated air within the limits of a single sector.

4. The drier as described in claim 3, together with a lint trap between the outlet of said moisture laden air and the atmosphere.
